FIG.1.

UNITED STATES PATENT OFFICE

2,631,876

AUTO DOOR LOCK

Hsiang Ju Lin, Cannes, France

Application May 3, 1950, Serial No. 159,828

3 Claims. (Cl. 292—51)

1

This invention relates to systems for locking simultaneously all of the doors of a multiple door vehicle and it relates particularly to a locking system whereby all the doors of an automobile may be locked and unlocked by means of a single exterior locking handle.

In accordance with the present invention, I have provided a simplified locking system including movable bolts for locking and releasing each of the doors of the vehicle, these bolts being projected and retracted by means of suitable actuating members mounted for movement in the pillars of the vehicle body adjacent to the free edges of the doors. The several actuating members for the bolts are interconnected by means of a closed hydraulic system including hydraulic cylinders or jacks which are arranged so that movement of one of the pistons of a jack will cause all of the other pistons to move simultaneously thereby actuating all of the bolts at the same time to lock or unlock the doors.

In order to provide a simple and rugged system which can be operated with a minimum of thought, the pistons are so arranged that outward movement of one of the pistons will actuate one or more bolts, while inward movement of the piston or pistons at the opposite end of the system will operate the locking bolts at the other end of the system. This arrangement of the cylinders or jacks is especially desirable inasmuch as it permits the operating handles which are connected with the pistons and exposed at the exterior and the interior of the vehicle to move in the same direction for locking and unlocking the doors.

Through the use of hydraulic connections between sturdy operating cylinders, a foolproof mechanism is provided which is not readily susceptible to damage and which is operable independently of other mechanisms of the vehicle.

For a better understanding of the present invention, reference may be had to the accompanying drawings in which:

Fig. 1 is a schematic layout of typical locking system embodying the present invention, parts thereof being shown in section and exaggerated in size to disclose details of construction;

Fig. 2 is a view in side elevation and partly in section of the device taken on lines 2—2 of Fig. 1;

Fig. 3 is a view in elevation and partly in section looking in the direction of the arrows 3—3 of Fig. 1; and

Fig. 4 is a view of the operating handle look-

2

ing in the direction of the arrows 4—4 of Fig. 1.

The invention will be described with reference to its use in a vehicle of the type having four doors. In this vehicle, the doors on both sides of the vehicle are hinged at their opposite vertical edges so that their free edges are adjacent a central pillar; that is, the front door on one side of the vehicle opens at its rear end while the back door on the same side of the vehicle opens at its front end. The invention is, however, equally applicable to vehicle door arrangements in which both of the doors are hinged at their rear edges or their front edges, as is the case in some body styles.

Referring now to the drawings, the vehicle body includes the central pillar 10 on the left-hand side of the car and the pillar 11 on the right-hand side of the car which lead into and form a support for the top or roof 12 of the vehicle. The pillar and top construction is conventional, does not form a part of the invention and therefore is not illustrated in detail. As shown in Fig. 2, the pillar 10 forms a dividing section between the front door 13 and the rear door 14, both of which are hinged to the body at their outer ends so that their inner free ends 13a and 14a substantially abut the sides of the pillar 10 when the doors are closed.

The doors may, of course, be provided with conventional locks and door handles. Both of the doors 13 and 14 further may be locked to the pillar by means of the pivoted bolts or latches 15 and 16 which are supported for rocking movement on the pivot pins 17 and 18. The outer ends of the bolts 15 and 16 are normally disposed within the side flanges 10a and 10b of the pillar 10 but can be projected into slots or recesses 19 and 20 in the abutting faces of the doors 13 and 14 by rocking their inner ends downwardly. The bolts 15 and 16 are normally retracted by means of coil springs 21 and 22, respectively, anchored at one end to the interior of the pillar and at the opposite end to the inner ends of the bolts 15 and 16. Other types of springs or their equivalent may be substituted for the springs 21 and 22, of course.

The bolts 15 and 16 have semi-circular notches 23 and 24 in their inner ends for engagement with an actuating pin 25 which projects outwardly from a rack member 26. The rack member 26 is guided in a bearing or bushing 27 which is fixed to the interior of the pillar in any suitable way so that the rack member can reciprocate axially. The pin 25 engages inner ends of the bolts and is received in the notches 23 and 24 on downward movement and thereby swings

the outer ends of the bolt members into the slots 19 and 20 to lock the doors to the pillar. Upward movement of the rack member 26 in conjunction with the springs 21 and 22 rocks the inner ends of the bolts 23 and 24 upwardly so that the outer ends of the bolts are withdrawn from the slots 19 and 20 to release doors 13 and 14 from the pillar 10.

The pillar 11 at the opposite side of the vehicle also carries a similar pair of bolt members 29 and 30 which cooperate with the front and rear doors 31 and 32 in the same way as the bolts 23 and 24 cooperate with the doors 13 and 14. The bolts 29 and 30 are actuated by means of a pin 33 which is mounted on the end of and projects outwardly from the piston rod 34 which is fixed to a piston member 35 reciprocable in a hydraulic cylinder 36. The cylinder 36 is fixedly supported in the pillar 11 by means of a ring clamp 37 or other suitable support rigidly connected to the pillar 11.

The upper end of the cylinder 36 is connected by means of a conduit 38 to the upper end of another similar cylinder 39 in the pillar 10. The cylinder 39 also has a piston 40 therein. A piston rod 41 is connected to the piston 40 and projects from the lower end of the cylinder 39. The lower end of the piston rod 41 is in the form of a rack 42. The rack 42 is connected with the rack member 26 by means of an idler pinion 43 mounted rotatably on a shaft or pin 44 extending transversely of the pillar 10 and supported therein.

The pistons 35 and 40 are so positioned in their respective cylinders that when the piston 40 is in its lowest position, piston 35 is in its upper position. Therefore, when the piston 40 is retracted by downward movement of the rack member 26 to project the bolts 23 and 24, the piston rod 34 is projected so that the pin 33 thereon will engage and project the bolts 29 and 30 to lock the doors 31 and 32. In this way, movement of either of the piston rods 34 and 41 will cause movement of the other piston rod to either lock all the doors simultaneously or unlock them simultaneously.

To facilitate operation of the locking system, the rack member 26 is provided with a handle member 45 which is exposed on the outside of the pillar 11 through a slot 46 to permit up and down movement of the handle. If desired, the piston rod 34 may also have an inwardly extending handle 47 which permits operation of the bolts from the interior of the car.

It will be understood that the locking handle 45 has a conventional key lock or its equivalent so that it can be locked in the closed position to prevent entry of the car. Any conventional key lock may be used for this purpose.

The system, while described above with reference to the use of two pairs of bolts actuated by two cylinders, is equally well adapted for use with vehicle doors which do not have their free edges adjacent to a common pillar. In this arrangement, it is only necessary to provide separate cylinders like the cylinder 36 for three of the doors while a single master cylinder 39 is used for the fourth door. The three auxiliary cylinders will, of course, individually have a smaller liquid capacity than the master cylinder 39 so that all of the piston rods can move a sufficient distance to operate the bolts.

Also, while pivoted bolts have been disclosed in the system, it will be understood that reciprocable bolts may be used equally well. These

bolts may be actuated by suitable tapered cams or wedges on the ends of the rack member 26 and the piston rod 34 to project and retract the bolts.

Accordingly, it will be understood that the above-described embodiment is illustrative and should not be regarded as limiting the scope of the following claims.

I claim:

1. A system for locking simultaneously pairs of vehicle doors, each pair having free edges adjacent to a common body pillar, comprising a pair of bolts pivotally mounted in each pillar and having adjacent inner notched ends and outer ends movable into and out of locking engagement with the free edges of the doors adjacent to said pillar, a rack mounted in one of said pillars for reciprocation toward and away from said bolts, a pin on said rack engageable in said notches to move said bolts, a cylinder mounted in said one pillar, a piston reciprocable in said cylinder, a piston rod comprising a rack portion fixed to said piston, an idler pinion mounted in said one pillar and connecting said rack and rack portion for reciprocation in opposite directions, a cylinder and piston in the other pillar, a pin fixed to said piston for moving the bolts in said other pillar and a conduit connecting said cylinders to form therewith a closed hydraulic system for transmitting movement of one of said pistons to the other.

2. The system set forth in claim 1 comprising a handle fixed to said rack and accessible from the exterior of said one pillar for reciprocating said rack.

3. A system for locking simultaneously all of the doors of a multiple door vehicle, comprising a locking bolt for each door pivotally mounted in a portion of said vehicle adjacent to a free edge of each door, each bolt having an outer end part pivotally movable into engagement with a portion of its associated door to retain it against opening movement, and out of engagement with said portion to release said door, the inner end of each bolt having a notch therein, actuating members mounted for reciprocation adjacent to the inner ends of said bolts and having portions engageable with and disengageable from the notch in the associated bolt, a piston connected to each actuating member for movement with the latter, a cylinder receiving each piston, at least one conduit connecting said cylinders to form therewith a closed hydraulic system to transmit movement of one piston to another piston, a rack having a handle thereon accessible from the exterior of said vehicle for moving the rack, a rack portion fixed to an adjacent piston, and an idler pinion meshing with said rack and rack portion for moving said rack and piston simultaneously in opposite directions.
